UNITED STATES PATENT OFFICE.

NATHANIEL IRVING BROWN, OF SEYMORE, INDIANA.

DESIGN FOR A SIGN.

Application filed August 18, 1927. Serial No. 23,133. Term of patent 14 years.

To all whom it may concern:

Be it known that I, NATHANIEL IRVING BROWN, a citizen of the United States, and a resident of the city of Seymour, county of Jackson, and State of Indiana, have invented a new, original, and ornamental Design for Sign, of which the following is a specification, reference being had to the accompanying drawings, forming a part thereof.

In the drawings Fig. 1 is a side elevation of the invention. Fig. 2 is a top plan view thereof.

I claim:

The ornamental design for a sign, as shown.

NATHANIEL IRVING BROWN.
